DESIGN FOR A VENDING MACHINE

Louis A. M. Phelan, Rockton, Ill.

Application August 11, 1941, Serial No. 102,782

Term of patent 14 years

To all whom it may concern:

Be it known that I, Louis A. M. Phelan, a citizen of the United States, residing at Rockton, in the county of Winnebago and State of Illinois, have invented a new, original, and ornamental Design for Vending Machines, of which the following is a specification, reference being had to the accompanying drawing, forming a part thereof.

The figure is a perspective view of a vending machine showing my new design.

The side not shown is substantially identical to the side shown, the rear being substantially plain.

I claim:

The ornamental design for a vending machine, as shown and described.

L. A. M. PHELAN.
